S. HITE.
TANK HEATER.
APPLICATION FILED AUG. 26, 1916.

1,256,560.

Patented Feb. 19, 1918.

SAMUEL HITE -
N. S. Hite Attorney

UNITED STATES PATENT OFFICE.

SAMUEL HITE, OF ATWOOD, INDIANA.

TANK-HEATER.

Specification of Letters Patent. Patented Feb. 19, 1918.

1,256,560.

Application filed August 26, 1916. Serial No. 117,089.

To all whom it may concern:

Be it known that I, SAMUEL HITE, a citizen of the United States, residing at Atwood, in the county of Kosciusko, State of Indiana, have invented a new and useful 5 Tank-Heater; and I do hereby declare the following to be a full, clear, and exact description of the invention, such as will enable others skilled in the art to which it applies to make and use the same.

The present invention relates to certain new and useful improvements in tank heaters, and has for its object to provide a device of this character which embodies novel features of construction whereby the water in a drinking trough or fountain can be readily kept from freezing in cold weather.

Further objects of the invention are to provide a device of this character which is 20 comparatively simple and inexpensive in its construction, which will warm the water within the trough in an effective manner so that it will not freeze in cold weather, which admits of the heater being detached from 25 the trough when not in use, and which can be quickly assembled or taken apart.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following description and accompanying drawing, in 35 which:—

Figure 1 is a front elevation of a tank heater constructed in accordance with the invention, portions of the smoke pipe being 40 broken away.

Fig. 2 is a vertical longitudinal sectional view through the same.

Fig. 3 is a top plan view with the upper end of the smoke pipe removed.

45 Corresponding and like parts are referred to in the following description and indicated in all the views of the drawings by the same reference characters.

Referring to the drawings, the numeral 1 50 designates a drinking trough which may be conveniently formed of sheet metal and which is open at the top, said trough being supported in an elevated position in any suitable manner, as by means of the stands 2. A flue 3 extends upwardly from an 55 opening in the bottom of the trough 1, the

lower end of flue having a water tight connection with the edges of the opening, while the upper end of the flue extends above the top of the trough and is provided with the 60 diametrically opposed bayonet slots 4. The water 5 in the trough 1 surrounds the flue 3, the said flue being preferably located at substantially the center of the trough.

Extending transversely across the bottom 65 of the trough 1 is a pair of guide members 6 which have a parallel relation to each other, and may be conveniently formed from Z bars. The exterior of the trough 1, and the bottom thereof, with the exception of the 70 area between the guide members 6 is covered with a layer 7 of insulating material, such as asbestos, thereby preventing radiation of the heat from the sides of the trough.

A fire box 8 is adapted to be applied to 75 the bottom of the trough, the top of the fire box being provided with lateral flanges 9 which engage the guide members 6, and being also provided with an opening 10 which registers with the lower end of the flue 3 80 when the fire box is in position. The front of the fire box is provided with the door 11 for closing the opening through which fuel is placed into the fire box. Below the door 11 is a second door 12 which has a damper 85 controlled draft opening 13 therein, said door normally closing the opening through which the ashes are removed. This fire box can be readily inserted in position or removed therefrom, and may be constructed of 90 sheet metal, being adapted to burn wood or coal as occasion requires.

After the fire box has been mounted in position a smoke pipe 14 is inserted in the flue 3, the lower end of the smoke pipe being 95 slightly contracted at 14^a, so as to tightly engage the edges of the opening 10 in the top of the fire box. This smoke pipe is provided with the conventional form of damper 15, the damper spindle 16 projecting upon 100 opposite sides of the smoke pipe and engaging the bayonet slots 4 in the top of the flue 3 when the smoke pipe is in position. This smoke pipe extends a suitable distance above the trough 1, the upper end thereof being 105 provided with a cap 17 which has a screen 18 fitted therein to prevent the escape of live sparks. When the parts are properly assembled and a fire started in the box 8 the water within the trough 1 is heated so that 110 it will not freeze in cold weather. In mild weather when it is not necessary to use the

heater, the fire box and smoke pipe can be readily removed. All of the parts are readily accessible for the purpose of making repairs, and the entire device can be constructed of sheet metal, so that the cost thereof will not be excessive.

In order to insure the heating of the water at the ends of the tank which is some distance from the fire box and flue, a series of 10 heating pipes are extended along the bottom of the tank from the fire box toward both ends of the tank. In the present instance elbows 20 are shown as threaded in openings in the bottom of the tank which register 15 with openings 21 in the top of the fire box, the said elbows being arranged upon opposite sides of the flue 3. A manifold 22 is arranged near each end of the tank and is connected to the elbows 20 by small pipes 20 or tubes 23. The heated gases from the furnace may thus pass upwardly through the openings 21 in the top of the fire box and circulate through the pipes 23 and manifolds 22 so as to heat the water in the ends of 25 tank which would not, especially in extremely cold weather, be heated by the fire box and flue 3 alone.

Having thus described the invention, what I claim as new and desire to secure by 30 Letters Patent, is:—

1. A tank water heater including a trough, a flue extending upwardly through the trough and opening through the top and bottom thereof, transverse guide members 25 extending across the bottom of the trough, a removable fire box provided with side flanges which are slidably engaged by the before mentioned guide members to support

the fire box, said fire box having an opening in the top thereof adapted to register with 40 the flue, a smoke pipe extending through the flue and having the lower end thereof projecting into the opening in the top of the fire box to hold the fire box in operative position, and means for obtaining an interlocking connection between the smoke pipe and the flue to hold the smoke pipe in position.

2. A tank water heater including a trough, a flue extending upwardly through the trough and opening through the top and bottom thereof, the upper end of the flue being provided with diametrically opposed bayonet slots, transversely disposed guide members extending across the bottom of the trough, a removable fire box provided with 55 side flanges which are slidably engaged by the said guide members to support the fire box, said fire box having an opening in the top thereof adapted to be brought into registry with the flue, a smoke pipe extending 60 through the flue and having the lower end thereof in engagement with the opening of the fire box to hold the fire box in position, and a damper within the smoke pipe, said damper including a spindle of which the 65 ends are adapted to interlock with the bayonet slots of the flue to hold the smoke pipe in position.

In testimony whereof I have signed my name to this specification in the presence of 70 two subscribing witnesses.

SAMUEL HITE.
